HINGE FOR SLIDING WINDOW SCREENS

Filed March 9, 1925

Inventor

Charles F. Geschickter
By Lewis S. Clarkson
his Attorney

UNITED STATES PATENT OFFICE

CHARLES F. GESCHICKTER, OF WASHINGTON, DISTRICT OF COLUMBIA

HINGE FOR SLIDING WINDOW SCREENS

Application filed March 9, 1925. Serial No. 14,288.

One of the objections to the sliding window screen as now most commonly employed is that it is necessary to bodily remove the screen from its slides whenever it is desired 5 to wash the windows. It is more or less difficult to do this by reason of the weight of the screen, and frequently the screen becomes overbalanced and falls to the ground which results in damage to the screen.

10 The object of my invention is to provide a combined sliding and hinge screen which may be easily installed and is of such construction that the cost will not materially exceed the cost of the ordinary commonly used 15 screen.

Another object of my invention is to provide in the place of the usual blind stops channel blind stops which serve the dual capacity of blind stops and slideways for the 20 screen.

A further object of my invention is to provide for use with the channel blind stops a screen frame having hinges, one leaf of which is adapted to interlock with a slide in the 25 said channel blind stops; and with these and other objects in view, my invention consists of the parts and combination of parts as will be hereinafter more fully set forth.

In the drawings:

30 Figure 1 is a front elevation of a window frame and its sash with my improved screen mounted in said frame, the screen being shown in closed position.

Figure 2 is an enlarged detail perspective 35 view of one of the side members of a window frame showing the installation of my invention thereto.

Figure 3 is a sectional view through the lower portion of Figure 1.

40 Figure 4 is a perspective view of my improved hinge.

Figure 5 is an enlarged detail view.

Figure 6 is a perspective view of one of the slide pins.

45 Figure 7 is a perspective view of the face plate for said slide pins.

The reference numeral 1 designates a window frame having the side members 2 and 3 and sill 4, all of which may be of the usual 50 construction with the exception that I do not

employ the usual solid blind stops, but use in place thereof the blind stops 5 and 6 constructed of channel metal as clearly shown in Figures 2 and 3. The blind stops are secured to the window frame by means of the screws, or 55 other securing devices 7.

The blind stop 5, as more clearly shown in Figure 3, is provided with an inwardly laterally extending flange 8 at the free edge of which there is an inwardly extending flange 9, 60 these flanges constituting in effect a substantially L-shape flange, which term I may use in the claim for the sake of clearness and brevity.

The blind stop 10 has one long arm or side member 11, which extension of the arm functions as a guard covering the joint between the blind stop and the hinge side of the screen 12, as more clearly shown in Figure 3.

At predetermined intervals in the blind stop 10 I secure channel sections 13 and 14, 70 the outer free edges of the side members of which are bent inwardly at right angles to provide overhang flanges 15. These sectional channel members may be secured in any suitable manner within the blind stop 10. The 75 channel section 13 is provided with a stop 16 to be hereinafter referred to.

The screen 12 is provided on one of its hanging stiles, the hinge 17, the leaf 18 of which is provided at each end with a flange 80 19 bent inwardly at right angles to the leaf 18, said flanges 19 having recesses 20 in each end thereof. The flanges 19 may be described as substantially T shaped.

With the hinges 17 secured to the screen 85 12 the screen is positioned with the hinge leaves 18 above the upper edges of the channel sections 13 and 14 whereupon the flanges 19 of the hinge leaf 18 are free to be projected within the blind stop 6 whereupon the downward movement of the screen causes the flanges 19 to move within the channel sections 13 and 14, the flanges 15 of the channel sections 13 and 14 interlocking in the recess 20 of the flanges 19 thereby securely interlocking the hinges in position within the blind stop 6 whereupon the screen is free to be moved on its hinges without fear of displacement, or disconnection from the blind stop 6. In order to prevent the lower edge of the 100

screen 12 from binding on the window sill 4 I provide the stop 16 which is so positioned as to hold the screen in the proper position relative to the window sill 4, as will be readily understood. In order to prevent the hinge leaves 17 and 18 from assuming intimate contact relation when the screen is in its closed position I provide a stop 21 projecting above the face of the hinge leaf 17 and have shown 10 this stop as being integral with one of the screws to secure the leaf 17 to the screen frame.

On the other, or swinging side of the screen I provide slidable pins 22 (preferably two in 15 number) slidably mounted in the side stile of the screen and adapted as shown in Figure 3, to be projected within the blind stop 5. This pin is provided with a lock element 23 which, as shown in Figure 3, will lock the pin 22 in its operative position by reason of the fact that in that position the lock member 23 is at right angles to the slot 24 of the face plate 25, which face plate is secured to the side stile of the screen. This pin 22, as shown 20 in the drawing, is provided with a suitable hand hold, as shown.

Now with the parts in the position shown in Figure 2 and in the sectional view of Figure 3 the screen is in its position relative to 30 the window frame in which it may be swung outwardly on its hinges, after the bolts or pins 22 are withdrawn from the blind stop 5. With the parts as shown in Figures 1 and 35 3 the screen is in position to be slid in the blind stops 5 and 6, and in order to hold the screen in the position at the top of the window frame I provide friction springs 26 which are secured in the bottom of the blind stop 5, said springs not only holding the 40 screen across the upper portion of the window frame, but also exert the pressure in the direction of the hinged side of the screen thereby insuring the hinge in its proper seating and sliding action.

45 It will be understood that changes may be made in the details of construction shown without departing from the scope of the appended claim.

What I claims is:

50 In a window, a channel blind stop, a channel section secured in said stop and having its outer edges bent inwardly toward each other, a hinge one leaf of which is provided with an inwardly bent flange at each end, a recess in 55 each flange adapted to receive the outer bent edges of the channel section and thereby lock the hinge on the blind stop.

In testimony whereof I affix my signature.

CHARLES F. GESCHICKTER.
